DESIGN FOR A BRIEF CASE

John P. Wege, St. Paul, Minn., assignor to Brown
& Bigelow, St. Paul, Minn., a corporation of Minnesota

Application January 24, 1936, Serial No. 60,762

Term of patent 3½ years

To all whom it may concern:

Be it known that I, John P. Wege, a citizen of the United States, residing at St. Paul, county of Ramsey, and State of Minnesota, have invented a new, original, and ornamental Design for a Brief Case, of which the following is a specification, reference being had to the accompanying drawings, forming part thereof:

I claim:

The ornamental design for a brief case, as shown and described.

JOHN P. WEGE.
